(57) **CLAIM**

The ornamental design for a webcam mount for flexible positioning, as shown and described.

DESCRIPTION

FIG. 1 is a left side elevational view of a webcam mount for flexible positioning, the undisclosed right side being the mirror image;

FIG. 2 is a top plan view thereof; and,

FIG. 3 is a perspective view thereof.

The broken line showing of a support surface is for illustrative purposes only and forms no part of the claimed design.
